FLOOR LAMP

Application filed June 19, 1928. Serial No. 286,585.

The present invention relates to floor lamps and more especially to a floor lamp adapted for indirect illumination.

The present invention contemplates a floor lamp, or the like, provided with an upwardly directed lamp socket placed so as to dispose the lamp inside a metal deflector adapted to reflect most of the light upwardly toward the ceiling. In order that this deflector may not appear dark and uninteresting, the deflector is associated with a light transmitting and distributing device whereby a portion of the light is redirected onto the outside of the metal deflector to illuminate the same. An other portion of the light is diffused downwardly so as to illuminate the standard which supports the deflector and lamp parts.

According to the present invention, the metal deflector and the glass diffuser are mounted so as to be removable without in any way interfering with the wiring for the lamp. In this manner the deflector and diffuser may be removed for cleaning and as desired. Glass of various colors may be used and an appropriate ornament applied to the deflector to fit the floor lamp for use in various settings.

The accompanying drawings show, for purposes of illustrating the present invention, one of the many possible embodiments in which it may take form, it being understood that the drawings are illustrative of the invention rather than limiting the same.

In these drawings:

35 Figure 1 is a side elevational view of a floor lamp;

Figure 2 is a sectional view of the upper part of the floor lamp with parts in elevation;

40 Figure 3 is an enlarged detailed view showing the structure for supporting the diffuser and deflector; and

Figure 4 is a fragmentary view of a detail.

While the form of construction used in supporting the other parts of the floor lamp may be varied in considerable detail, it is for convenience here shown as being made up to have a base 10 carrying a column 11. The base and column are fastened together by a 50 nipple 12 and nut 13. The column 11 is pro-

vided with passageways 14 leading up to tapped holes 15. In the present form of construction three of these tapped holes are employed to receive three pipes 16. These pipes taken together, make up a standard and may extend upwardly and diverge slightly as indicated.

The upper ends of the pipes 16 are threaded as indicated at 17 in Figure 3 and collars 18 are threaded in place. These collars 18 support a large stamping 19 which acts as a socket cover and as a support for the glass diffuser which has been mentioned. This stamping 19, as here shown, extends inwardly from the upper ends of the pipe 16 and downwardly to provide a conical socket cover 20 in which is mounted a socket 21. This socket is preferably carried on a bushing 22 soldered in place in the stamping 19. The switch in the socket is actuated by a lever 23 connected to a tassel 24. The stamping 19 is held in place against the collars 18 by means of hickeys 25 threaded onto the upper end of the pipe. The wiring is brought up through one of the hickeys and taken into the 75 socket and mounted in this manner.

The stamping 19 extends outwardly and upwardly as indicated at 26 to support a glass diffuser 27. This diffuser is in the form of an annular ring or collar of opal glass. As indicated in the drawings, it is generally of U-shaped cross section of sufficient depth so that light from the lamp L may be partly reflected from the lower surface of the glass collar upwardly so as to pass out 85 through the upper surface and then diffused as indicated. The upper end of each hickey 25 is threaded to receive a short rod or nipple 29. A metal reflector 30 rests on the upper surface of the diffuser 27 as indicated and is held in place by nuts 31 threaded onto the rods 29. The upper end of the rods 29 are threaded and each carries a nut 32 adapted to support straps 33 fastened to the inside of a metal deflector 34.

The lower edge 35 of the metal reflector preferably rests lightly on the glass 27. The principal support for the deflector, however, is through the bracket 33 in nut 32. Nuts 36 are provided to clamp the straps 33 in place 100

against the nuts 32. This arrangement provides for some adjustability for the support for the metal deflector, and provides a rigid substantial structure.

5 The lamp standards may be stiffened, and the appearance of the lamp improved by employing two spiders 40 and 41 having prongs 42 projecting into holes in the pipes 16. These spiders are fastened together by a 10 pipe 43 and knobs or nuts 44 housed in stamping 45, as shown in Figure 4.

The present form of floor lamp is one in which practically all of the light is directed upwardly. A small portion of the total light 15 emitted is diffused downwardly from the glass ring or collar 27 so as to illuminate the standard, while another portion is diffused from the upper part of the collar or ring 27 to illuminate the outside of the deflector.

20 The upper face of the glass ring may be clear glass, if desired. The deflector and socket cover may be ornamented in any desired manner. The general shape of the floor lamp is strikingly like a flower pot on a 25 stand, and use may be made of this similarity when the lamp is to be used in various settings.

It is obvious that the invention may be embodied in many forms and constructions 30 within the scope of the claims, and we wish it to be understood that the particular form shown is but one of the many forms. Various modifications and changes being possible, we do not otherwise limit ourselves in 35 any way with respect thereto.

We claim:

1. A floor lamp comprising a base, a standard comprised of a plurality of spaced apart vertical members, a downwardly dished 40 stamping carried by the upper ends of said members and extending downwardly between the same, a lamp socket housed in the stamping, an upwardly extending lamp in the socket, and an opaque deflector supported 45 above the upper ends of the members and surrounding the lamp to deflect light upwardly.

2. A floor lamp comprising a base, a standard comprised of a plurality of spaced apart vertical members, a downwardly dished 50 stamping carried by the upper ends of said members, a lamp socket housed in the stamping, an upwardly extending lamp in the socket, a shallow annular ring of diffusing glass resting on the stamping, and a deflector 55 carried from the standard and extending upwardly and outwardly from the ring, the outside of the deflector being illuminated by light from the ring.

60 3. A floor lamp comprising a base, a standard comprised of a plurality of spaced apart vertical members, a downwardly dished stamping carried by the upper ends of said 65 members, a lamp socket housed in the stamping, an outwardly extending lamp in the sock-

et, a shallow annular ring of diffusing glass resting on the stamping, a reflector surrounding the neck of the lamp and acting on downwardly directed light to reflect it onto the glass ring, and a deflector carried from the 70 standard and extending upwardly and outwardly from the ring, the outside of the deflector being illuminated by light from the ring.

4. A floor lamp comprising, a base, a standard having a plurality of upwardly extending members, an upwardly opening socket cover supported by the members and disposed between the members, an upwardly opening lamp socket in the socket cover, a lamp in the socket, means for securing the socket cover in place on the members, an annular ring of diffusing glass of U-shaped cross section supported on the upper edge of the socket cover, rods extending upwardly 80 from the securing means, and an outwardly and upwardly flaring deflector supported from the upper ends of the rods to be above the diffusing ring in a position to be illuminated by light therefrom. 85

5. A floor lamp comprising, a base, a standard having a plurality of upwardly extending members, an upwardly opening socket cover supported by the members and disposed between the members, an upwardly opening lamp socket in the socket cover, a lamp in the socket, threaded means for securing the socket cover in place on the members, an annular ring of diffusing glass of 90 U-shaped cross section supported on the upper edge of the socket cover, rods extending upwardly from the securing means, the upper ends of the rods being threaded, and an outwardly and upwardly flaring deflector supported above the diffusing ring in a position to be illuminated by light therefrom, the deflector being adjustably supported in the rods. 95

6. A floor lamp comprising, a base, a standard having a plurality of upwardly extending members, one of which is tubular, an upwardly opening socket cover supported by the members and disposed between the members, an upwardly opening lamp socket in the socket cover, a lamp in the socket, means for securing the socket cover in place on the members, one of said means being in the form of a hickey to accommodate wiring from the tubular member, an annular ring of diffusing glass of U-shaped cross section supported on the upper edge of the socket cover, rods extending upwardly from the securing means, and an outwardly and upwardly flaring deflector supported from the upper ends of the rods to be above the diffusing ring in a position to be illuminated by light therefrom. 110

7. A floor lamp comprising a base, a standard extending upwardly therefrom, an annular ring of diffusing glass of U-shaped 120

cross section, an opaque support at the upper end of the standard and closing the aperture in the lower side of the glass ring, a light source positioned slightly above the ring, a reflector extending inwardly from the lower side of the glass ring to intercept light directed toward said opaque support and scatter it outwardly into the glass ring, and an opaque deflector extending upwardly and outwardly from the inner portion of the upper side of the glass ring, the light diffused through the upper face of the ring illuminating the outside of the deflector, the light diffused from the lower side of the ring illuminating the standard and base.

5 Signed at Meriden, in the county of New Haven and State of Connecticut, this 14th day of June, 1928.
